UNITED STATES PATENT OFFICE.

HEINRICH WILLEM KAREL DE BREY, OF THE HAGUE, NETHERLANDS.

PORTABLE CABINET TALKING MACHINE.

Application filed June 14, 1926, Serial No. 116,024, and in the Netherlands June 18, 1925.

My present invention relates to portable cabinet talking machines, its object being a talking machine of this type, which, although occupying little space, provides for an unobstructed sound chamber of ample capacity. With this object in view, I suggest to adapt the driving gear for being wholly or partly moved out of the cabinet so that the free space thus established within the cabinet constitutes, or forms part of, the sound chamber.

In order that my invention may be well understood, I shall now proceed to describe one preferred embodiment thereof with reference to the annexed drawing, in which Fig. 1 illustrates a vertical sectional elevation of the talking machine with the lid of the cabinet down, Figs. 2 and 3 being a side elevational view and a plan view, respectively, of the talking machine in its operative position.

The cabinet 1 is provided with a lid 2 hinged thereto and further with a drawer or slideable casing 3 containing the usual spring motor (not known), adapted to be wound up as at 4 by means of a crank and, when running down, to drive the turntable 5. If the lid is down, the crank 6 is located within the same and partly projects through a hole 7 in the top of the casing 3, while the sound arm 8, which also is located within the lid, partly projects through a circular aperture 12 in the top of the cabinet and is supported by a pin 13. The sound box 10, provided with the usual stylus bar or the like, is carried by a goose neck 9 pivotally connected with the sound arm 8.

To put the machine in operation, the lid 2 is opened and the casing 3 drawn out by the handle 14. Thereupon, the sound arm is taken off the pin 13 and placed upon another pin (not shown) centrally within a second aperture 19 in the top wall of the cabinet, see Fig. 3. A record 16 is placed upon the turntable, the goose neck 9 with the sound box 10 swung over and the door 15 opened, when the machine is ready for use. The door 15 closes the opening 17 in a side wall of the casing and is here shown as hinged at 18, but may be mounted in any suitable or desirable manner. The distance, through which the casing 3 is to be drawn out of the cabinet, depends upon the diameter of the record to be reproduced.

As will be seen, the space within the cabi-

net, which originally was occupied by the casing 3, now forms part of the sound chamber, which, therefore, is of ample capacity although the dimensions of the talking machines in its inoperative position according to Fig. 1 are minimum.

It will be understood that it is not necessary for the casing 3 to be slideable within the cabinet. It could as well be hinged to the cabinet so as to be adapted to be swung out, or be adapted to be moved out of the cabinet in any other suitable manner, provided only that the space within the cabinet originally occupied thereby is adapted to function as a sound chamber, or as a part thereof.

What I claim is:—

1. A portable phonograph machine comprising a motor and record support, a tone arm, and a casing for housing said support and tone arm, said casing including a lid mounted to move in and out of closed position covering said tone arm and support, means in the casing for supporting said tone arm in operative and inoperative positions, said motor and record being mounted in said casing to be displaced through an opening in a side wall of the casing, the casing providing a sound chamber when said motor casing is so displaced and said tone arm is in operative position and a second opening in the side wall of said casing to permit sounds to emanate from said sound chamber.

2. A portable phonograph comprising a casing, a motor-housing drawer slidably mounted in said casing and adapted to be moved into and out of said casing, said motor-housing drawer having means for supporting a playing record, a tone arm, a support in the casing having means for removably holding the tone arm in operative position, the interior of said casing providing a sound chamber communicating with said tone arm when said drawer is moved out of the casing and tone arm is in operative position.

3. A portable phonograph comprising two telescoping members, one of said members containing a motor and record support means, a sound amplifying chamber being provided when said telescoping members are distended, and a tone arm to co-operate with the record on said record support means and communicating with said sound chamber, said sound chamber having an outlet opening.

4. A portable phonograph comprising two telescoping members, one of said members containing a motor and record support means, a sound amplifying chamber being provided when said telescoping members are distended, and a tone arm to co-operate with the record on said record support means and detachably communicating with said sound chamber, said sound chamber having an outlet opening, and means within said sound chamber for supporting said tone arm when disconnected from operative position.
5. A portable phonograph comprising a casing having a lid, record supporting means mounted in the casing, a sound amplifying chamber provided in the casing, a wall overlying said amplifying chamber having two openings therein, a tone arm adapted to fit one of said openings to operatively communicate with the sound chamber when the lid is opened, a support under the other of said openings, said tone arm being adapted to extend through the other of said openings when in inoperative position and engage said support, whereby the tone arm is

held against the under side of the lid when the lid is closed.

6. A portable phonograph comprising a casing having a lid, record supporting means mounted in the casing, a sound amplifying chamber provided in the casing, a wall overlying said amplifying chamber having two openings therein, a tone arm adapted to fit one of said openings to operatively communicate with the sound chamber when the lid is opened, a support under the other of said openings, said tone arm being adapted to extend through the other of said openings when in inoperative position and engage said support, whereby the tone arm is held against the underside of the lid when the lid is closed, said record supporting means being mounted to move out of said casing to enlarge said sound amplifying chamber and to be positioned to co-operate with said tone arm when the latter is in operative position.

In testimony whereof I affix my signature.

HEINRICH WILLEM KAREL de BREY.
